(57) **CLAIM**

The ornamental design for a desk-chair combination frame, as shown and described.

DESCRIPTION

This application is related to U.S. Provisional application 60/892,468, filed Mar. 1, 2007, the disclosure of which is incorporated herein by reference, and to U.S. Design patent application Ser. No. 29/304,425, filed Feb. 29, 2008, which is currently pending, and the disclosure of which is incorporated herein by reference.

FIG. 1 is a perspective view of the desk-chair combination frame showing our new design;

FIG. 2 is another perspective view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top plan view thereof; and,

FIG. 8 is a bottom plan view thereof.

Any broken line illustration of environmental structure in the drawings is not part of the design sought to be patented.
